N° 533

ORNAMENTAL DESIGN FOR RAILINGS

Patented Dec. 14, 1852.

Nicholas P. Horton of Cincinnati Ohio.
Letter Patent No 533 Dated Dec 14th 1852.

The schedule referred to in this Letter Patent and making part of the same.

City of Cincinnati
Hamilton County
State of Ohio }

To all whom it may concern.

Be it known that I Nicholas P. Horton, of the County and State aforesaid have invented or produced a new ornamental Design for Railings and I do hereby declare the following to be descriptive thereof reference being had to the annexed Drawings making part of this specification.

The design may be said to consist of several Members as follows.

Member A is a semicircular head (1) enclosed and circumscribed by a rectangular one (2).

Member B consists of two scrolls (3) united by fillet (4) and having their intervening space occupied by a pair of *Fluer-de-lis* terminals, (5, 6) upon a stalk (7).

Member C, consists of an open rectangular head (8) enclosing a rosette (9).

Member D consists of a pair of Lyre formed scrolls (10) enclosing a group of tendrilis (11) in the form of a Grecian Aersteria, springing from a shield (12) the neck of the Lyre is bound with a fillet (13) Balls (14) terminate the End Members.

What I claim as my invention and design to secure Letters Patent for is a design for ornamental Iron Railings as described in the above Specification and illustrated in the accompanying drawings.
